UNITED STATES PATENT OFFICE

2,047,843

CIRCUIT BREAKER

Ludwig S. Walle, Lansdowne, Pa., assignor to
 General Electric Company, a corporation of
 New York

Application February 1, 1935, Serial No. 4,448

8 Claims. (Cl. 200—144)

5 My invention relates to circuit breakers, more particularly to interrupting or arc extinguishing devices therefor and has for an object the provision of a simple and reliable interrupting device of the compression chamber type.

10 In my copending application, Serial No. 667,856, filed April 25, 1933, entitled "Circuit breakers" which is assigned to the same assignee as the present invention, I have disclosed and broadly claimed a circuit breaker comprising a compression chamber provided with a fixed contact, a cooperating contact movable between open and closed circuit positions with a snap action, and sealing means associated with the movable contact and the compression chamber arranged to provide for snap action of the movable contact and substantially to seal the compression chamber. As pointed out in the above identified application, when an arc is drawn between the separating contacts, a rapidly increasing pressure is built up within the compression chamber which serves quickly to extinguish the arc.

15

20

25

It will be apparent that the magnitude of the pressure built up within the compression chamber depends not only upon the volume of the compression chamber and upon the magnitude of the current interrupted but also upon the effectiveness of the sealing means provided. The problem of effectively sealing the compression chamber is complicated not only by the magnitude of the pressure which may be of the order of 1000 pounds per square inch, but by the necessity of providing for snap action of the movable contact between its extreme open and closed circuit positions. I have found that it is desirable, especially when utilizing circuit breakers of this type to interrupt large currents at relatively high voltages, to provide an additional sealing means which is effective when the movable contact is in open circuit position gas tightly to seal the compression chamber so as to prevent the leakage of any gases therefrom. The provision of such an auxiliary sealing means will of course result in the attainment of higher pressures in a shorter interval of time and consequently, in a quicker interruption of the arc without burning of the contacts. Accordingly, it is a further object of my invention to provide a circuit interrupting device of the compression chamber type provided with valve means for gas tightly sealing the compression chamber when the movable contact is in open circuit position.

30

35

40

45

50

In carrying out my invention in one form, I provide a circuit breaker having a compression chamber for enclosing a fixed contact and a rel-

atively movable contact, the movable contact being provided with a shoulder arranged to seat against a wall of the compression chamber when the movable contact is in open circuit position, gas tightly to seal the compression chamber. Means are also provided for operating the movable contact between open and closed circuit positions with a snap action. More specifically, I provide a compression chamber having an aperture in one wall thereof for supporting and guiding a reciprocally movable contact, means associated with the apertured wall and the movable contact for substantially sealing the compression chamber during movement of the contact between open and closed circuit positions, and means comprising a valve seat formed in the wall of the compression chamber and a valve head carried by the movable contact for gas tightly sealing the compression chamber when the movable contact is in its open circuit position, the volume of the compression chamber being of such magnitude that the gas entrapped at atmospheric pressure in the chamber is heated by the arc formed between the contacts upon interruption of a predetermined maximum current to such an extent that gas pressures are generated in the chamber sufficiently high to effect extinguishment of the arc, i. e., gas pressures of the order of 1000 pounds per square inch.

For a more complete understanding of my invention, reference should now be had to the drawing in which Fig. 1 is a plan view of a circuit breaker provided with an interrupting device embodying my invention. The cover of the circuit breaker has been removed and certain parts have been omitted in order to illustrate the operating mechanism therefor. Fig. 2 is a sectional elevational view taken along line 2—2 of Fig. 1, and Fig. 3 is a partial, detailed sectional view of one end of the interrupting device with the movable contact shown in open circuit position.

Referring now to the drawing, I have shown my invention in one form as applied to a multi-pole circuit breaker comprising a base 10 formed of molded insulating material and arranged to support a plurality of improved interrupting or arc extinguishing devices 11 embodying my invention, an operating mechanism indicated generally by the reference numeral 12 and a unitary trip device indicated generally by the reference numeral 13.

Each of the interrupting or arc extinguishing devices 11 comprises a pressure resisting cylinder 14 preferably formed of brass or of an alloy, commonly known as "Everdur", one form of

which may be composed of 93% copper, 3% silicon and 1% manganese. Within the cylinder 14, I provide a fixed contact 15, a reciprocally movable contact 16, the abutting ends of which contacts are preferably formed of suitable low resistance material, such as silver-molybdenum, for example, and a cylindrical liner 17 of kerosene-free fiber. In order to provide a gas tight closure for one end of the cylinder 14 and a rugged insulating support for the contact 15, a plurality of insulating bushings 18 and 19 and a cup-shaped member 20 of suitable material such as soft copper, are arranged between an annularly extending portion 21 on the contact 15 and an inwardly extending flange 22 on one end of the cylinder 14. One end of the contact 15 is threaded as indicated at 23 and a nut 24 is provided for cooperation therewith, a corrugated washer 25 of insulating material being interposed between the nut 24 and the flange 22. It will be observed that the working surfaces of the flange 22 and the annularly enlarged portion 21 are beveled so that when the nut 24 is tightened down on the threaded end of the contact 15, the insulating bushings 18 and 19 and the washer 25 will be wedged into place to form a rigid support for the contact 15 and a gas tight closure for one end of the cylinder 14. It will also be seen that the soft copper member 20 will be spread by the annular portion 21 to form a gas tight seal between the cylindrical liner 17 and the contact 15, and to longitudinally fix the liner 17 relative to the cylinder 14.

Closure means are also provided for the other end of the cylinder 14 which comprise a cylindrical cap 26 threadedly engaging the cylinder 14 and provided with a sealing gasket 27 arranged to form a gas tight seal between the cap and the cylinder. Threadedly engaging the cylindrical cap 26 is a plug or ring 28 in which the movable conductor 16 is slidably journaled. In order to substantially seal this end of the cylinder 14 while at the same time providing for snap action of the movable contact 16, I provide a plurality of flexible washers 29 and 30, the washer 30 being provided with an inwardly projecting cylindrical extension for exerting a wiping action on the movable contact 16 when the contact is operated to open circuit position. In addition to its function as a sealing means between the end closure of the cylinder 14 and the movable contact 16, the washer 30 serves the additional purpose of preventing the deposit of metal vapor on the movable contact, a certain amount of which is produced when the circuit breaker interrupts currents of large magnitudes.

In addition to the washers 24 and 30 for substantially gas tightly sealing the compression chamber during movement of the movable contact 16, it is also highly desirable to provide means for entirely gas tightly sealing the compression chamber when the movable contact 16 is in its open circuit position. Accordingly, I provide a conical valve seat 31 in the inner face of the cylindrical cap 26 and an annularly extending shoulder 32 on the movable contact 16. When the movable contact is in its extreme open circuit position the shoulder 32 engages the valve seat 31, as shown in Fig. 3, to provide a gas tight seal for this end of the compression chamber. It will be observed that in the embodiment shown the valve seat 31 is formed in a separate member 33 which is supported in the cylindrical cap 26. This member 33 may be special heat re-

sisting material such as stainless steel, or kerosene-free fiber in order to prevent welding of the movable contact to the valve seat. For low voltages, as for instance voltages below 440 volts, it may be desirable to form the valve seat 31 directly in the face of the cylindrical cap 26.

It will, of course, be apparent that the movable contact 16 may be supported entirely within the compression chamber and operated between open and closed circuit positions by suitable reciprocal operating means extending through a wall of the pressure resistant casing, in which case a shoulder corresponding to the shoulder 32 would be provided on the reciprocal means for cooperation with the valve seat 31 gas tightly to seal the compression chamber.

The electrical circuit for each pole of the circuit breaker is substantially the same and may be traced from one of the terminal members 34 arranged at one end of the base 10 to the fixed contact 15 by way of the conductor 35, which is clamped to the fixed contact 15 by a nut 36, through the contacts 15 and 16, across the operating mechanism indicated generally at 12 by way of the flexible conductors 37, and through the trip device indicated generally at 13 by way of the conductors 38 and 39 to a terminal member 40. It will be observed that the movable contact 16 is not insulated from the metallic cylinder 14 and in order to provide sufficient creepage distance between the fixed contact 15 and the metallic cylinder 14, the washer 25 is corrugated as shown, and the inner diameter of the cylindrical liner 17 is stepped as indicated, one end of the liner being spaced from the metallic cylinder 14 as shown at 41.

Suitable insulating barriers are provided for preventing flashover or short circuit between the individual poles of the circuit breaker, the barriers 42 and 43 being integral with the base member 10 and extending from the respective opposite ends thereof to the operating mechanism 12 and the trip device 13, respectively, which are provided with insulating barriers 44 and 45, respectively, arranged substantially in alignment with the barriers 42 and 43.

Although any suitable mechanism may be provided for operating the movable contacts 16 between open and closed circuit positions with a snap action, either individually or simultaneously, I have shown for purposes of illustration an operating mechanism for simultaneously actuating all of the movable contacts 16 of the type described and claimed in a copending application of Leonard J. Linde, Serial No. 5,036, filed February 5, 1935, entitled "Circuit breakers," which application is assigned to the same assignee as the present invention.

This operating mechanism which is indicated generally at 12 is supported adjacent one end of the interrupting or arc extinguishing devices 11 on a frame which comprises a pair of spaced supporting walls 46 and a supporting block 47, the walls and the block being mounted on one of the metallic cylinders 14 and suitably fastened thereto as by the screws 48. Each of the supporting walls 46 includes an elongate portion extending along the cylinder 14 and a laterally extending portion which overhangs the end of the cylinder 14 adjacent the movable contact 16. Extending between the overhanging portions of the supporting walls 46, a plurality of pivot pins 49, 50 and 51 are provided for respectively supporting a pair of spaced parallel arms 52, a U-75

shaped operating member 53 and a pair of three-point or substantially triangular shaped toggle links 54. The U-shaped operating member 53 is provided with an insulating handle 55 which extends through a suitable aperture 56 in the circuit breaker cover 57, and the adjacent ends of the spaced arms 52 opposite from the ends supported from the pivot pin 49 carry an operating pin 58 the ends of which respectively extend through suitable slots 59 in the toggle links 54. In order to brace the spaced arms 52 and to maintain them in proper parallel relation, a pair of cross pins 60 and 61 are provided extending therebetween. These pins are omitted in Fig. 1 in order to simplify the drawing.

Connected to each of the substantially triangular toggle links 54 is a second toggle link 62, the other end of which pivotally engages a pin 63 which is supported by the legs of a U-shaped member 64, the yoke portion of which surrounds and is rigidly connected to a pivoted crossbar 65. The crossbar 65 is journaled at its ends in a pair of bearings 66 fastened to the base 10 and extends across the three poles of the circuit breaker for simultaneously operating all of the contacts 16 between open and closed circuit position, each of the contacts 16 being connected thereto by means of a resilient lost-motion connection which includes a pin 67 carried by the legs of a U-shaped operating finger 68 and extending through a slot 69 in a block 70 which is rigidly secured, as by a press fit, to the extending end of the movable contact 16. As will be seen, the extending end of the movable contact 16 is drilled as indicated at 71 to provide a housing for a compression spring 72, one end of which bears against the contact 16 and the other end of which bears against the pin 67. It will be observed that as the toggles each comprising the links 54 and 62 are concurrently made or broken, the cross bar 65 is rotated and consequently the movable contacts 16 are operated between open and closed circuit positions.

In order to make and break the toggles with a snap action, a pair of overcenter spring devices are provided. Although any suitable type of overcenter spring device may be provided, each of the two devices shown comprises an inverted U-shaped frame 74, one end of which is pivotally connected to the operating pin 58 carried by the switch arms 52, and a yoke member 75 carried by a pin 76 which is carried by and extends laterally from the U-shaped operating member 53. Arranged within each U-shaped frame 74 is a pair of compression springs 77, the respective ends of which bear against the end portion of the frame and against a movable plate 78 arranged between the legs of the frame and carried by a pair of plungers 79, the opposite ends of which extend slidably through the end of the frame 74 and are fastened to the supporting yoke 75 carried by the pin 76. It will be apparent that the springs 77 are arranged to resist relative movement between the yoke 75 and the frame 74 in the direction of the plungers 79 and tending to further operate them and act as an extremely strong tension spring connected between the operating member 53 and the operating pin 58.

The circuit breaker is also arranged for automatic operation in response to abnormal current conditions and accordingly, the operating mechanism is provided with a U-shaped tripping member 80 pivotally supported on the pin 50 and normally latched in the position shown in Fig. 2 by the trip device 13, the latching portion of

which engages the yoke portion 81 of the tripping member. The tripping member 80 is provided with a pair of extending fingers 82 which are arranged to engage the operating pin 58 when the operating member is moved from its normal latched position in order to move the triangular toggle links 54 about the pivot 51 to break the toggles and operate the contacts 16 to open circuit position. In order quickly to move the tripping member 80 from its latched to its tripping position, a pair of straps 83 is provided, each of which is connected between a pin 84 on the tripping member 80 and a movable thrust bar 85 arranged in the slots 86 in the frame walls 46 and engaging the adjacent ends of a pair of tripping springs 87, the other ends of which are supported by a stationary thrust bar 88. It will be observed that when the tripping member 80 is in the latched position shown in Fig. 2 of the drawing, the tripping springs 87 will be compressed and will therefore be effective upon the release of the tripping member to operate the tripping member in a clockwise direction about its pivot point 50, thereby causing the fingers 82 to engage the operating pin 58. The force exerted by the tripping springs 87 is sufficient to move the operating pin 58 downwardly as seen in Fig. 2 against the force exerted by the overcenter springs 77, and thereby to break the toggle and move the contacts 16 to their open circuit positions. The tripping member 80 may be returned to the latched position shown in the drawing, after an operation thereof to trip the circuit breaker, by moving the handle 55 downwardly, the operating member 53 being provided with a shoulder 89 which is arranged to operate with a shoulder 90 on the tripping member.

Any suitable trip device may be provided for releasably latching the tripping member 80 in its latched position and for releasing the tripping member upon the occurrence of abnormal current conditions. For best operation, however, I prefer to use a trip device of the type described and claimed in a copending application of John L. Lappin, Serial No. 4,659, filed February 2, 1935, entitled "Circuit breakers", which application is assigned to the same assignee as the present invention.

This trip device 13 may be described for the purposes of the present application as comprising a sub-base 91 suitably fastened to the circuit breaker base 10, the before-mentioned insulating barriers 45 being formed integral therewith. Supported centrally of the sub-base 91 is a frame comprising the spaced walls 92 between which are supported a latch plate 93, pivoted at 93a, a U-shaped impact member 94, pivoted at 94a, and a U-shaped reset member 95, pivoted at 95a. The latch plate 93 is provided with a finger 96 arranged to engage the yoke portion 81 of the tripping member 80 in latching relation, and the yoke of the U-shaped impact member 94 is provided with an over turned portion 97 to provide a striking surface for engaging a portion of the latch plate 93 nested therewith. Each leg of the impact member 94 carries a pin 98 extending through a slot 99 in one of the supporting walls 92 and arranged to engage one of the two cam fingers 100 which constitute the legs of the U-shaped reset member 95, the yoke portion of which is interposed in the path of the tripping member 80. Suitable springs 101 are provided for operating the impact member 94 about its pivot in a counter-

clockwise direction as viewed in Fig. 2 and thereby cause the overturned portion 97 to strike the latch plate a hammerlike blow and thereby move the latch to release the tripping member 80, and a pair of resetting springs 102 are arranged to operate the reset member 95 about its pivot to return the impact member 94 to the position shown in the drawing after each operation thereof to striking position.

10 The impact member 94 is normally held in the position shown in the drawing by a trip bar 103, pivoted at 103a, which extends across the three poles of the circuit breaker and is normally biased by a spring 104 to engage a finger 105 on 15 the impact member and thereby hold the impact member against movement on its pivot by the springs 101. Associated with each pole of the circuit breaker is a thermal and a magnetic device for moving the trip bar 103 about its 20 pivot in a counterclockwise direction as viewed in Fig. 2 to release the impact member 94. Each thermal device comprises a bimetallic element 106 arranged to be heated in accordance with the current through the associated pole of the 25 circuit breaker and adapted when heated to engage an adjustable insulating button 107 carried by the trip bar 103 to move the trip bar about its pivot. As shown, each of the bimetallic elements has the shape of an inverted U and is 30 connected in the circuit of its associated switch pole so as to carry a portion of the current. Each of the magnetic devices comprises a U-shaped magnet 108 partially surrounding one of the conductors 39 and arranged to attract a 35 common armature 109, pivoted at 109a, which extends across the three poles of the circuit breaker and is provided with a finger 110 for engaging an adjustable pin 111 on the trip bar 103 in order to move the trip bar about its pivot 40 in a counterclockwise direction as viewed in Fig. 2 to release the impact member when the armature is attracted by one or more of the magnets 108.

It will be apparent that upon the occurrence 45 of abnormal current conditions through the circuit breaker, the trip bar 103 will be moved either by the thermal or by the magnetic means, depending upon the character of the abnormal condition, to release the impact member 94 for 50 operation by the springs 101 to strike the latch plate 93 with a hammerlike blow and release the tripping member 80, whereupon the tripping member 80 will be moved by the tripping springs 87 to open the circuit breaker contacts.

55 While I have shown a particular embodiment of my invention, it will be understood of course that I do not wish to be limited thereto, since many modifications may be made and I, therefore, contemplate by the appended claims to 60 cover any such modifications as fall within the true spirit and scope of my invention.

What I claim as new and desire to secure by Letters Patent of the United States is:

1. An electric circuit interrupter comprising a 65 pair of contacts one of which is movable between open and closed circuit positions, walls of pressure resistant material enclosing said contacts to form a compression chamber of such size that the gas entrapped at atmospheric pressure in said chamber is heated by the arc formed 70 between said contacts upon interruption of a predetermined maximum current to generate in said chamber high gas pressures on the order of 1000 pounds per square inch, whereby said maximum current may be interrupted without detri- 75

mental burning of said contacts, means extending through a wall of said chamber for operating said movable contact, and valve means responsive to movement of said one contact associated with said operating means and said one wall for gas-tightly sealing said compression chamber when said movable contact is in open circuit position whereby said high gas pressures are quickly generated.

2. An electric circuit interrupter comprising a 10 pair of contacts one of which is reciprocally movable between open and closed circuit positions, walls of pressure resistant material enclosing said contacts to form a compression chamber of such size that the gas entrapped at atmospheric pressure in said chamber is heated by the arc formed between said contacts upon interruption of a predetermined maximum current to such an extent that gas pressures are generated in said chamber sufficiently high to effect extinguishment of the 20 arc, said movable contact extending through one of said walls, a valve seat comprising an annular member formed of heat resistant material supported on said one wall surrounding said movable contact and a shoulder on said movable contact 25 arranged to engage said valve seat for gas-tightly sealing said compression chamber when said movable contact is in open circuit position.

3. An electric circuit interrupter comprising a 30 pair of contacts one of which is movable between open and closed circuit positions, a compression chamber comprising a casing of pressure resistant material enclosing said contacts, said casing having a volume of such size that the gas entrapped therein at atmospheric pressure is heated by the 35 arc formed between said contacts upon interruption of a predetermined maximum current to generate in said casing high gas pressures of 1000 pounds per square inch or more whereby said maximum current is interrupted without detrimental 40 burning of said contacts, reciprocal means extending through an aperture in said casing for operating said movable contact, and means comprising a shoulder portion on said reciprocal means for engaging said casing adjacent said 45 aperture gas-tightly to seal said chamber when said movable contact is in open circuit position whereby said high gas pressures are quickly generated.

4. An electric circuit interrupter comprising a 50 pair of contacts one of which is reciprocally movable between open and closed circuit positions, walls of pressure resistant material enclosing said contacts to form a compression chamber of such size that the gas entrapped at atmospheric pressure in said chamber is heated by the arc formed 55 between said contacts upon interruption of a predetermined maximum current to such an extent that gas pressures are generated in said chamber sufficiently high to effect the extinguishment of 60 the arc, said movable contact extending through one of said walls, means associated with said wall and said one contact for substantially sealing said compression chamber during movement of said one contact, and a shoulder on said movable contact for engaging said wall gas-tightly to seal 65 said chamber when said one contact is in open circuit position.

5. An electric circuit interrupter comprising a 70 pair of contacts one of which is reciprocally movable between open and closed circuit positions, walls of pressure resistant material enclosing said contacts to form a compression chamber of such size that the gas entrapped at atmospheric pressure in said chamber is heated by the arc formed 75

between said contacts upon interruption of a predetermined maximum current to such an extent that gas pressures are generated in said chamber sufficiently high to effect extinguishment of the arc, means extending through one of said walls for operating said movable contact, means associated with said one wall and said operating means for substantially sealing said compression chamber during movement of said one contact, 10 and valve means associated with said one wall and said operating means for gas-tightly sealing said compression chamber when said movable contact is in open circuit position.

6. An electric circuit interrupter comprising a 15 pair of contacts one of which is reciprocally movable between open and closed circuit positions, walls of pressure resistant material enclosing said contacts to form a compression chamber of such size that the gas entrapped at atmospheric pressure in said chamber is heated by the arc formed between said contacts upon interruption of a predetermined maximum current to such an extent that gas pressures are generated in said chamber sufficiently high to effect the extinguishment of the arc, said movable contact extending through one of said walls, means associated with said wall and said one contact for substantially sealing said chamber during movement of said one contact, a valve seat comprising an annular 25 member formed of heat resistant material supported on said wall surrounding said one contact and a shoulder on said one contact for engaging said valve seat when said one contact is in open

circuit position gas-tightly to seal said compression chamber.

7. An electric circuit interrupter comprising a pair of contacts one of which is reciprocally movable between open and closed circuit positions, a cylinder of pressure resistant material surrounding said contacts, a cap for one end of said cylinder provided with an aperture for guiding said reciprocal contact, closure means for gas-tightly closing the other end of said cylinder, said closure 10 means including a support for said other contact, means associated with said cap and said reciprocal contact for substantially sealing said one end of said cylinder during movement of said reciprocal contact, and valve means associated with 15 said cap and said reciprocal contact for gas-tightly sealing said one end of said cylinder when said reciprocal contact is in open circuit position.

8. A circuit breaker comprising a pair of relatively movable contacts, resilient means for operating one of said contacts between open and closed circuit positions with a snap action, a compression chamber comprising a casing of pressure resistant material enclosing said contacts, said one contact extending through an aperture in 25 said casing, means associated with said casing and said one contact for substantially sealing said chamber during the snap movement of said one contact, and valve means associated with said casing and said one contact for gas-tightly sealing 30 said chamber when said one contact is in open circuit position.

LUDWIG S. WALLE.
